EXPLOSIVE TRIP FOR WELL DEVICES

Clarence E. Burt, Los Angeles, Calif., assignor to
Baker Oil Tools, Inc., Vernon, Calif., a corpora-
tion of California

Application May 16, 1941, Serial No. 393,751

10 Claims. (Cl. 166—12)

This invention relates to apparatus capable of initiating operation of well devices lowered or supported in a well bore on the end of a wire or other flexible line.

Certain devices, such as bridge plugs, gun perforators, bailers, etc., are lowered into a well bore or casing on the end of a wire line. In some designs, a go-devil or similar weight is dropped down the wire line for engagement with the particular well device to initiate its operation. Obstructions, tight places, or crooked portions in the well bore often prevent passage of the go-devil into engagement with the particular tool connected to the wire line, or the go-devil strikes the device with insufficient force to initiate its operation, or with a force so great as to inflict damage upon it.

Accordingly, it is an object of the present invention to provide an apparatus which obviates the above noted defects by causing more positive engagement of a go-devil with a well device to institute its operation.

A further object of the invention is to provide a go-devil apparatus employable in connection with a wire line in which it is unnecessary to lower or drop the go-devil along the wire line to begin operation of a well device connected thereto.

This invention has other objects that will become apparent from a consideration of the embodiment shown in the drawing accompanying and forming part of the present specification. This form will now be described in detail, but it is to be understood that such detailed description is not to be taken in a limited sense, since the scope of the invention is best defined by the claims appended hereto.

Referring to the drawing:

Figure 1 is a side elevation of a tripping apparatus disclosed in conjunction with a bridge plug;

Figure 2 is a longitudinal section on an enlarged scale of part of the arrangement shown in Figure 1;

Figure 3 is a view similar to Figure 2 with certain of the parts in a different operative position; and

Figure 4 is a diagrammatic view of a circuit employable in connection with the apparatus constituting the present invention.

The apparatus A shown in the drawing is designed for connection to the lower end of a wire line B to initiate operation of a suitable well device C, which in the present instance takes the form of a bridge plug adapted to be set in

packed off condition within a well casing D. The apparatus includes a go-devil or similar inertia member 10 normally held in retracted position, but adapted to be released by an explosive force for projection toward the well device to produce its operation.

In the specific apparatus illustrated, the wire line B is in the form of a cable having a conductive core 11 terminating in a contact 12 with 10 in a firing head 13 threadedly secured to a sub 14 to which the cable is attached in any suitable manner. A tie rod 15 is screwed into the lower end of the firing head, extending downwardly therefrom through the go-devil 10, which is held initially in an upper position adjacent the firing head by a shear screw 16 threaded through the go-devil head 17 for receipt within a circumferential groove 18 provided at the upper end of the tie rod 15. This frangible screw 20 normally holds the go-devil 10 in elevated position on the tie rod away from operative engagement with the well device C. Its release and downward movement is obtained by imposing a downwardly directed force on its head 17 to shear the screw 16 and allow its dropping along the tie rod 15 into operative engagement with the particular well device secured to the tie rod.

30 This force is obtainable by firing a powder charge 19 contained within the firing head 13, which, upon ignition, will expand into the firing chamber 20 for action upon a tripping pin or piston 21 held in a socket 22 at the upper end of the go-devil by a set screw 23 or other suitable element. Prior to disruption of the shear screw 16, the tripping pin 21 is received within 35 and closes a bore 24 forming the lower end of the firing chamber 20, abutting against a lead sealing disc 25, which, in turn, engages a steel washer 26 extending across the firing chamber. The lead sealing disc 25 prevents well fluids from entering the firing chamber 20 and dampening the powder charge 19.

The powder charge 19 is detonated by a cartridge 27 received within a central bore 28 in the upper portion of the firing head. This cartridge 27 is positioned in a sleeve 29 yieldably mounted within a retainer 30; a helical spring 31 seating upon a lower shoulder 32 on the retainer and constantly urging the sleeve 29 and cartridge 27 carried thereby upwardly to hold a contact 33 on the latter in engagement with the contact 12 on the end of the conductor 11.

One form of circuit employable for discharging the powder within the cartridge 27 is dis-

closed in Figure 4, in which a battery 34 is provided as a source of current, one terminal being grounded and the other end connected to a lead 35 running to a switch 36. One end of the switch is connected to a grounded condenser 37, from where a lead 38 extends to a second switch 39 controlling the discharge from the condenser through the conducting line 11 in the wire cable to the contact 33 at the top of the cartridge connected to a heating filament 40 10 therewithin. The other end of the filament is grounded to complete the circuit.

When the cartridge 27 is to be fired, the charging switch 36 is closed one or more times to build up a charge in the condenser 31 of sufficient magnitude to pass through the conductive line 11 and ignite the filament 40 in the cartridge. When such charge is available in the condenser, the discharging switch 39 is closed to permit its passage to the cartridge 27, the filament 40 becoming heated and setting off the cartridge charge, which in turn ignites the powder charge 19. The gases resulting from the ignition of the powder charge expand into the firing chamber 20 and exert an explosive force downwardly upon the steel washer 26, lead disc 25, tripping pin 21 and go-devil 10 to shear the screw 16 and force the go-devil downwardly along the tie rod 15 for initiating operation of the particular well device C to which the tripping apparatus A is connected.

A sufficient powder charge 19 must be used in the firing head 13 to overcome the hydrostatic head of fluid acting upwardly upon the cross-sectional area of the tripping pin 21, and thereby counteracting the explosive force of the charge. The initial pressure in the firing chamber 20 is atmospheric, while the external pressure acting on the tripping pin depends upon the depth to which the apparatus is lowered and the fluid level in the well bore. However, the powder charge used in the device is ample to overcome this hydrostatic pressure differential, and also the resistance offered by the shear screw 16, to produce downward propulsion of the go-devil 10. In any event, the powder charge should be insufficient in quantity to inflict damage upon the apparatus as a result of its detonation.

As specifically disclosed in the drawing, the apparatus is employed for tripping a wire line bridge plug C. The details of such plug may be found in United States Patent 2,225,143. It consists essentially of upper and lower packing members 41 for preventing passage of fluid in both directions between the plug and well casing D, and upper and lower sets of segmental slips 42 for preventing movement of the plug in either direction after their engagement with the wall of the casing. As shown in Figure 1, the packings and slips are in retracted position, the tool being supported through a suitable tripping mechanism (not shown), and a sleeve 43, which is herein disclosed as secured to a sinker bar 44 attached to the tie rod 15. The wire line tripping mechanism also includes a rod 45 extending through the sleeve 43, which has an anvil or abutment 46 at its upper end projecting outwardly in opposite directions through elongated slots 47 in the sleeve. Upon downward movement of the tripping rod 45 with respect to the sleeve, release of the bridge plug elements 41, 42 is accomplished, as fully explained in the patent referred to.

This tripping rod 45 is moved downwardly by a generally cylindrical weight 48 having pivoted latches 49 provided with inwardly directed noses

50 resting upon the upper end 51 of the sinker bar 44 to hold the weight in an upper position removed from engagement with the anvil 46. Leaf springs 52 engage the ends of such latches to hold their noses in position on the sinker bar.

It will be noted that the go-devil 10 is initially positioned above the tripping weight 48. Upon release of this go-devil as a result of igniting the powder charge 19, it enters the central bore 48a of the weight 48, its end engaging the inclined noses 50 on the latches to move them outwardly from engagement with the sinker bar 44, permitting the weight 48 to drop downwardly and engage the anvil or abutment 46. The weight is heavy enough to move the tripping rod 45 downwardly within the sleeve 43 to an extent limited by the lower ends of the sleeve slots 47. This action effects tripping of the bridge plug and the setting of its packing and slip elements 41, 42 in engagement with the casing D. Following such tripping action, the firing apparatus, go-devil, tripping weight, sleeve, tripping rod and associated tripping elements are released from the bridge plug and removed to the surface of the well bore.

I claim:

1. An apparatus adapted to be lowered in a well bore on a wire line, including a firing head, a movable weight, releasable means for preventing movement of said weight with respect to said head, and explosive instrumentalities within said head for releasing said means to enable dropping of said weight with respect to said head to a position wherein said weight initiates operation 30 of a well device within said well bore.

2. An apparatus adapted to be lowered in a well bore on a wire line, including a firing head having a combustion chamber adapted to contain an explosive charge, piston means normally closing an end of said combustion chamber, a movable weight releasably secured to said head, and means for detonating said explosive charge to move said piston means within said chamber to release said weight from said head.

45 3. An apparatus adapted to be lowered in a well bore on a wire line, including a firing head having a combustion chamber for containing an explosive charge, a movable weight releasably secured to said head, piston means normally closing said combustion chamber and engageable with said weight, and means for firing said explosive charge, whereby said piston means is forced against said weight to effect its release from said head.

55 4. An apparatus adapted to be lowered in a well bore on a wire line, including a firing head having a combustion chamber for containing an explosive charge, a movable weight releasably secured to said head, means normally closing said combustion chamber and engageable with said weight, and means responsive to passage of current through said wire line for firing said explosive charge, whereby said closing means is forced against said weight to effect its release from said head.

60 5. An apparatus adapted to be lowered in a well bore on a wire line, including a firing head having a combustion chamber for containing an explosive charge, a movable weight, frangible means securing said weight to said head, means normally closing said combustion chamber and engageable with said weight, and means for firing said explosive charge, whereby said closing 70 means is forced against said weight to disrupt

said frangible means and effect release of said weight from said head.

6. An apparatus adapted to be lowered in a well bore on a wire line, including a firing head having a combustion chamber for containing an explosive charge, a depending rod secured to said firing head, a weight mounted on said rod, frangible means securing said weight to said rod adjacent said firing head, means normally closing said combustion chamber and engageable with said weight, and means for firing said explosive charge, whereby said closing means is forced against said weight to disrupt said frangible means and effect release of said weight from said rod.

7. In an apparatus embodying a bridge plug capable of being lowered in a well bore on a wire line and set within a well casing by an inertia member initially held in ineffective position by latches, said apparatus including a depending rod connected to said wire line the combination therewith of means for releasing said latches comprising a go-devil engageable therewith to effect their release, said go-devil being mounted on said rod and explosive instrumentalities for releasing said go-devil to move into engagement with said latches.

8. In an apparatus embodying a bridge plug capable of being lowered in a well bore on a wire line and set within a well casing by an inertia member initially held in ineffective position by latches, the combination therewith of a firing head having a combustion chamber for containing an explosive charge, a depending rod secured to said firing head, a movable weight mounted on said rod and releasably secured to said head, and means for detonating said explosive charge to release said weight and enable it to move into engagement with said latches to release said inertia member.

9. In an apparatus embodying a bridge plug capable of being lowered in a well bore on a wire line and set within a well casing by an inertia member initially held in ineffective position by latches, the combination therewith of a firing head secured to said wire line and having a combustion chamber for containing an explosive charge, means including a rod for connecting said bridge plug to said firing head, a go-devil slideable along said rod, frangible means for releasably securing said go-devil to said rod adjacent said firing head, means normally closing said combustion chamber and engageable with said go-devil, and means for firing said explosive charge, whereby said closing means is forced against said go-devil to disrupt said frangible means and enable said go-devil to move into engagement with said latches for releasing said inertia member.
10. In an apparatus embodying a bridge plug capable of being lowered in a well bore on a wire line and set within a well casing by an inertia member initially held in ineffective position by latches, the combination therewith of a firing head secured to said wire line and having a combustion chamber for containing an explosive charge, means including a rod for connecting said bridge plug to said firing head, a go-devil slideable along said rod, frangible means for releasably securing said go-devil to said rod adjacent said firing head, means normally closing said combustion chamber and engageable with said go-devil, and means for firing said explosive charge, whereby said closing means is forced against said go-devil to disrupt said frangible means and enable said go-devil to move into engagement with said latches for releasing said inertia member.
